UNITED STATES PATENT OFFICE.

ARNOLD MASTRONY, OF BRIDGEPORT, CONNECTICUT.

MOP HOLDER.

Application filed April 14, 1925. Serial No. 22,993.

This invention relates to a mop holder and has for an object to provide an improved holder of this type which will be very simple in construction and so may be manufactured at low cost, will be simple to operate and not likely to be easily gotten out of order.

It is also an object of the invention to provide a holder in which the operation of inserting the wiper in and removing it from the holder is greatly simplified, so that it may be performed much more easily and quickly than in the forms now generally in use.

With the foregoing and other objects in view, I have devised the construction illustrated in the accompanying drawing forming a part of this specification, similar reference characters being employed throughout the various figures to indicate corresponding elements. In this drawing,

Fig. 1 is a side elevation of my improved mop holder.

Fig. 2 is an end view thereof.

Fig. 3 is a transverse section substantially on line 3—3 of Fig. 1, and

Fig. 4 is a transverse section substantially on line 4—4 of Fig. 1.

One end portion of the handle is indicated at 10 to which is secured a cross bar 11 by any suitable means such as a screw 12. This cross bar is provided with an opening 14 adjacent one end in which the clamping bar 15 is mounted to slide. This bar is bent to substantially the shape shown in Fig. 1 to provide a clamping portion 16 arranged substantially parallel with the cross bar 11, in position to cooperate therewith to clamp the wiper 17, of any suitable material such as cloths, or cords against the cross bar. The shank of the clamping bar, after passing through the opening 14 a sufficient distance to permit the required movement, is bent inwardly or substantially parallel with the clamping portion 16 as indicated at 18 and is then bent away from the clamping portion, as shown at 19, where it passes through suitable openings 20 in a guide member 21 secured to the handle. This guide member in the form shown is substantially U-shaped to provide two spaced guide portions 22 but it may, of course, be of different forms. Associated with this guide is a flat spring 23 having an opening 24 through which the portion 19 of the shank passes, and this portion of the shank is provided with a series of teeth 25 to engage one side of this opening. The teeth are substantially straight on one side as shown to provide shoulders 26 to engage one side of the spring to prevent the clamping portion 16 from moving away from the cross bar and thus release the wiper, or in other words these shoulders hold the clamping portion 16 in position to clamp the wiper against the cross bar. The other side of these teeth are inclined, as shown at 27, so as to allow free movement of the clamping bar in the opposite direction. The outer end of this spring is curved substantially, as shown at 28, to provide a thumb piece for depression of the free end of the spring toward the handle, as indicated in dotted lines to release the clamping bar and allow its clamping portion to be moved away from the cross bar to release the wiper.

The operation will be apparent from the foregoing description. By pressing inwardly on the free end 28 of the spring the clamping bar may be moved away from the cross bar to the dotted line position, either by forcing it away or by holding the handle erect with the cross bar down when the clamping bar will move to this position by its own weight. It will then be apparent that the wiper 17 may be placed in position between the bars by inserting it laterally between the free ends of these bars because the clamping portion 16 is freed from the cross bar at the end opposite from the guide opening 14. After the wiper has been inserted it may be securely clamped against the cross bar by merely pushing the clamping portion 16 against the floor or some other object, the inclined sides of the teeth 25 allowing this movement, but the straight sides of the teeth coacting with the spring will automatically lock it in clamping position. The free end of this clamping portion is preferably bent toward the cross bar a short distance, as shown at 29, to more securely hold the wiper in position and prevent its sliding from between the two bars in use. It will be apparent that to release the wiper all that is necessary is to press inwardly on the free end of the spring 28 and allow the wiper to slide off the free end of the cross bar.

It will be apparent that this device is very simple in construction and may be manufactured at low cost. It will also be apparent that it is extremely simple to operate, and because one end of the clamping portion

16 is free from the cross bar the operation of inserting or removing the wiper is greatly simplified as it does not have to be threaded through the space between the bars as in the 5 old forms, but may be merely slid laterally into position between the two bars.

Having thus set forth the nature of my invention, what I claim is:

1. In a mop, a handle, a cross bar mounted 10 thereon having a guide opening adjacent one end, a clamping bar having a shank at one end mounted to slide in said opening and having a clamping portion extending substantially parallel with the cross bar and 15 free from the cross bar at its opposite end, additional guide means for the shank on the handle, and a spring catch engaging the shank, said shank being provided with notches having shoulders to engage said 20 spring and hold the clamping bar against movement in one direction and having their opposite sides inclined to allow movement of the bar in the opposite direction.

2. In a mop, a handle, a cross bar mounted 25 ed thereon having a guide opening adjacent one end, a clamping bar having a shank mounted to slide in said opening and having a clamping portion extending substantially parallel with the cross bar, and free from 30 the cross bar at the opposite end from said opening to allow the wiper to be inserted between the two bars by a lateral movement from said end, and releasable means on the handle to engage the shank and hold the 35 clamping bar against movement away from the cross bar.

3. In a mop, a handle, a cross bar mounted

thereon having a guide opening adjacent one end, a clamping bar having a shank mounted to slide in said opening and provided 40 with a clamping portion extending substantially parallel with the cross bar and free from the cross bar at the opposite end from said opening to allow the wiper to be inserted between the two bars by a lateral 45 movement from said end, a guide for the shank on the handle, and a spring having an opening for said shank, the shank being provided with teeth having shoulders on one side to engage the spring to prevent 50 separation of the bars and inclined on the other side to allow the clamping bar to slide freely toward the cross bar.

4. In a mop, a handle, a cross bar mounted 55 thereon having a guide opening adjacent one end, a clamping bar bent to substantially U-shape to form two spaced legs of different lengths, the longer leg being substantially parallel with the cross bar and forming a clamping portion to clamp the wiper against 60 the cross bar and being free from the cross bar at the end opposite to said opening, the portion of the bar between said legs being guided in said opening, the shorter leg having its free end bent away from the clamping portion and provided with a series of 65 teeth, a guide on the handle for said bent away portion, and a spring arranged to engage said teeth to hold the bar in clamping position, and releasable to allow removal of 70 the wiper.

In testimony whereof I affix my signature.

ARNOLD MASTRONY.
